COMPRESSOR UNLOADING MEANS

William F. Gibson, Dayton, Ohio, assignor to
 Chrysler Corporation, Highland Park, Mich., a
 corporation of Delaware

Application August 22, 1946, Serial No. 692,269

2 Claims. (Cl. 230—26)

1

My invention relates to the automatic control of the pumping capacity of small compressors such as used in refrigeration or air conditioning units of relatively small sizes. My invention is an improvement upon the invention disclosed and claimed in the patent to Neeson 2,185,473, dated January 2, 1940, and comprises means adapting the principles of the Neeson patent to unusually compact compressors. The invention of course may be used in larger sizes of compressors but its primary aim is to provide a smaller compressor with all of the advantages and functions which Neeson provided for larger sizes of compressors. Likewise it should be pointed out that the same physically dimensioned compressor having my invention may have a 1 H. P. motor at certain speeds such as 1,760 R. P. M. may have a 2 H. P. motor attached thereto which operates at 3,400 R. P. M. and so on so that in speaking of the various horsepowers mentioned above I do not intend to be limited thereto. Likewise it is to be appreciated that the same compressor may be attached to an internal combustion engine capable of speeds such as 6,000 to 10,000 R. P. M. and the total horsepower required to drive the compressor would correspondingly increase. It should be appreciated that the term "horsepower" is used as a relative indication of the maximum tonnage of refrigeration since in general a 1 H. P. motor is required for a 1 ton refrigeration compressor and so on. The foregoing figures are meant to indicate the field of usefulness of my invention in compressors of small sizes with respect to the ordinary sizes of compressors for corresponding horsepower-tonnage ratios. Likewise it should be appreciated that while the primary field of usefulness of the invention is in the refrigeration and air conditioning arts, a compressor utilizing my invention may be found of value in any field where a gas must be compressed.

A principal purpose for which my invention has been developed is in the air conditioning of passenger automobiles or the refrigeration of small delivery trucks for perishable commodities. One of the problems of such an application is to provide a compressor of sufficient capacity at idling or low traveling speeds of the internal combustion engine driving the vehicle to provide the required amount of refrigeration, and which will be capable of maintaining a relatively constant compressing effect throughout the higher ranges of speeds to a maximum speed of which the automotive engine is capable. An engine of this type idles at relatively slow speeds such as

2

600 to 800 R. P. M. and is capable of far higher speeds such as 3,600 to 7,000 R. P. M. Thus if an ordinary compressor is applied to such a use it must be capable of producing the maximum desired refrigeration at idling speed, for example two tons of refrigeration at 800 R. P. M. Such an ordinary compressor would therefore produce approximately 10 tons of refrigeration at an engine speed of 4,000 R. P. M. when the vehicle is traveling at 50 miles per hour. The 10 tons is not only five times more refrigeration than desired so that the compressor would have to cycle on and off in short bursts of operation, but the engine would be subjected to terrific overloads at higher operating speeds. The sudden shocks of application of this overload would be extremely dangerous to both the engine and the compressor. Therefore the primary object of my invention is to provide a compressor which will maintain a constant output, i. e., will have a capacity of two tons at idling speeds and will maintain a capacity of two tons up to the highest operating speed of the vehicle.

An object of the present invention relating to the foregoing is the protection of the automotive engine against ordinary careless driving practices. Although it is well known to most drivers that it should not be done, it is very common to observe a vehicle driver start his engine and press the accelerator to the floor board several times in rapid succession. If this were done with an ordinary compressor attached to the engine severe damage might result since the engine would be expected not only to overcome its own sluggishness when cold but to operate the compressor against its maximum load. An object of my invention is to provide a compressor which will permit of a greater chance that no damage will be done under such careless handling.

A further object of my invention is to provide a compressor having automatic capacity reduction of such small size that it may fit between the engine block and ornamental grill of an ordinary automotive vehicle or in other cramped quarters. The compressor herein illustrated is a two-ton compressor adapted to be driven by external means such as by an internal combustion engine, having 6 cylinders with automatic capacity reduction means applied to each cylinder, the overall dimensions of which are approximately 11 inches from end to end and 10 inches maximum diameter. While I have illustrated a six-cylinder compressor, it is to be appreciated that the invention may be applied to a compressor of fewer or more cylinders.

The foregoing objects and advantages of my invention will be more readily understood by reference to the accompanying drawings wherein like numerals refer to like parts throughout. In the drawings, Fig. 1 discloses a preferred embodiment of my invention taken substantially along the longitudinal center line thereof in a plane determined substantially by the line 4-4 of Fig. 2. Fig. 2 is an end view of the compressor looking at the front cover thereof. Fig. 3 is the opposite end view. Fig. 4 is a partial cross-section taken substantially in the plane of Fig. 1 and showing further details of an individual cylinder and unloading means. Fig. 5 is a view taken substantially along line 5-5 of Fig. 4.

The compressor comprises a main casting 10 to which is bolted a front cover 11 and a rear cover 12. The main casting is provided with internally extending struts 13 supporting a journal 14 which holds spaced sleeve bearings 15 and 16 adapted to support the greater portion of a crank shaft 17 having a reduced end 18 which extends outward through an opening in the cover 12. The reduced portion 18 extends through a sealing device 20 such as disclosed in the patent to Christman and McCortney, No. 2,200,413, dated May 14, 1940, so that the interior of the casing formed by the three separable castings may be sealed against the atmosphere. The reduced portion of the shaft 18 is adapted to be suitably driven in any convenient manner. The crank shaft 17 is provided with a crank pin 25 surrounded by a sleeve bearing 26 which supports the enlarged ends of the appropriate number of connecting rods 27. Each connecting rod carries a piston 28 which reciprocates within a cylinder sleeve 29 which extends through a suction annulus 30 extending circumferentially around the interior of the casting 10. The outer end of the sleeve is associated with a suction and discharge valve assembly 31 mounted within a cylindrical bore 32 extending radially inward through the casting 10. The valve assembly is retained in position by a safety spring 33 which is held compressed by a bolt attached cylinder head 34. Details of an appropriate valve assembly not herein readily apparent may be obtained from the patent to Neeson, No. 2,137,965, dated November 22, 1938, or the co-pending application of Lickteig, Serial No. 668,962, filed May 10, 1946. The bore 32 is connected by a pipe 36 to the interior of a ring-shaped discharge annulus 37 which is attached to a suitable valve assembly 38 adapted to connect the compressor to a refrigeration system of any suitable compressor-condenser-expander type. The gas compressed by the compressor and utilized in the refrigeration system returns to the compressor through a suction valve 39 which communicates with the interior of the suction annulus 30.

The crank pin 25 is provided with a pump driving pin 45 which engages a cross bar 46 extending from a stub shaft 47 adapted to drive a gear pump 48 having associated therewith a reversing disk 49 such as more fully disclosed and claimed in the co-pending application of Wentling, Serial No. 660,981, filed April 10, 1946. Lubricating oil is adapted to be drawn from a sump space 50 provided by the lowermost portion of the rear cover 12 through a passage 51 extending longitudinally of the wall of the casing 10 and leading to a passage 52 extending vertically upward in the front cover 11 and communicating with a passage 53 leading to a suction groove 54 in the pump cover 55 as more fully disclosed in said

Wentling application. The oil which is forced from the gear pump 48 passes through a discharge groove 60 which communicates with a passage 61 extending outward through the cover 11 to a radially extending passage 62 communicating with a longitudinal passage 63 which leads to the master valve of the unloader mechanism. The discharge groove 69 in the pump cover also communicates with a longitudinal passage 65 which leads to a vertically extending passage 66 having one end terminating in a longitudinal bore 67 within which is mounted a ball thrust bearing for the pump assembly as more fully detailed in said Wentling application. The opposite arm of passage 66 leads to a longitudinally extending passage 68 which carries the lubricant to the bearings 15, 16 and 26 as more fully disclosed in the patent to Neeson, No. 2,225,228, dated December 17, 1940. Oil which passes between the bearing surfaces returns to the sump portion 50 and is recirculated by the pump. While I have illustrated a pump of the type disclosed in the aforesaid Wentling application it is to be appreciated that other types of unidirectional pumps may be substituted therefor such as that disclosed in the patent to Neeson, No. 2,151,482, dated March 21, 1939, so that regardless of the direction of rotation of the compressor crank shaft 17 oil will flow through the compressor bearings. This is of particular importance in vehicle air conditioning and refrigeration since the means of attaching the compressor to the automotive engine may vary in various applications, in some respects requiring clockwise revolution and in others counter-clockwise revolution.

As disclosed in the patent to Neeson No. 2,185,473, dated January 2, 1940, the interior of the casing communicates with the suction annulus 30 through a suitable small opening or openings so that the interior of the end cover 12 is subjected to the same pressures as exist within the suction annulus. This pressure is a reflection of the load upon the refrigerating system. At any given speed the pressure of the gas returning from the refrigerating system will be higher when there is a greater heat load upon the system than when there is a lesser heat load; therefore, the pressure within the end cover 12 will increase in proportion to the higher load. This pressure causes a corresponding collapse of a flexible metallic bellows 70 extending outwardly through a boss 71 cast onto the cover 12. The inner surface of the inner end of the bellows 70 is attached to a valve operating rod 72 and the outer surface of the inner end of the bellows 70 is attached to an adjusting rod 73 which extends beyond the compressor. The rod 73 extends through a threaded, longitudinally slotted member 74 which carries an adjusting nut 75 adapted to operate against the wings of a washer 76 slidable longitudinally of the member 74 thereby to compress a spring 77 which extends from the member 76 to the inner end of the bellows 70. Longitudinal adjustment of the nut 75 determines the degree of compression of the spring 77 and hence the range of pressures required to collapse the bellows 70. As the bellows collapses the rod 73 moves outward and as it expands the rod moves inward. A guide nut 78 may be adjustably positioned on the end of rod 73 to guide it and to determine the amount to which the bellows 70 may expand inwardly. Suitable adjustment of nut 78 may totally collapse the bellows 70 for a purpose which will presently appear.

The inner end of operating rod 72 is pivotally attached to the short arm of a pair of cranks 1 which are pivoted at 2 to a fulcrum member 3 mounted upon the inner surface of the end cover 12. The long arms of the lever 1 are pin and slot connected to a longitudinally movable master valve 4 which extends through a longitudinal bore in the casing 10 into a longitudinal bore in a valve member 5 mounted in a cylindrical cavity 6 in the end of the casing 10. The valve member 4 terminates in a pair of spaced lands 79 and 80 separated by a reduced portion 81. The passage 63 previously described communicates with the annular space surrounding reduced portion 81 by means of a slot 82 through the member 5. As the bellows 70 contracts and expands the crank 1 moves the valve member 4 in and out to variable extents but the pump 48 will always be in communication with the space surrounding portion 81. As the land 80 moves longitudinally the space surrounding portion 81 will communicate with a plurality of slots 90 in the member 5 each of which communicates with one of a group of longitudinal passages 91 extending through the member 5 into the end cover 11.

Each passage 91 communicates with a passage 92 extending through the cover 11 to the outer end of a cylindrical cavity 93 adjacent each of the cylinders 29. The cavity 93 holds a piston 94 which is moved outwardly by the compression of a spring 95 which extends from a collar 96 on a longitudinally extending rod 97 to a portion of the wall of the annulus 30. If the particular groove 90 is in communication with the space surrounding the reduced portion 81 pressure from the pump will be applied to the cylindrical space 93 to move the piston 94 and rod 97 inwardly against the compression of spring 95. The rod 97 is pivotally connected at 98 to a yoke member 99, the arms of which extend to opposite sides of the cylinder 29. Referring more particularly to Figs. 4 and 5 it may be seen that each arm is bent downwardly at its end to provide an inclined portion 100 adapted to be moved radially outward as the arm moves outwardly when oil pressure is relieved and the piston 94 is permitted to move outwardly by the compression of spring 95, thus bringing the inclined portion 100 over an abutment 101 such as provided by the head of a rivet 102 extending through the wall of the annulus 30. Each portion 100 is provided with an upwardly extending lug 103 engaging the under surface of a ring 104 surrounding the sleeve 29. The ring 104 is held against the lugs 103 by a spring 105 compressed between the ring and a portion of the valve assembly. The ring 104 is provided with a plurality of arms 106 which extend radially outward in close contact with the wall of the cylinder sleeve 29 in the space between the cylinder sleeve and the spring 105. The outer ends of the arms 106 extend through the slots in the valve assembly which provide the suction passages whereby gas may enter the interior of the cylinder sleeve 29 from the suction annulus 30. In the position illustrated in Fig. 4 the arms 106 are spaced from the inner surface of a suction ring valve 107 which controls the passage of gas from the annulus to the cylinder. The piston 28 is shown at the bottom of its stroke which means that the suction valve 107 has been opened due to the greater pressure of the gas in the annulus 30 over the rarified gas caused by the expansion of the free space in the cylinder due to the retraction of the piston. As soon as the piston starts moving outward the pressure

within the cylinder will become greater, thus closing the suction valve. As soon as pressure within the cylinder becomes great enough a discharge valve 108 will be lifted to permit the gas to be discharged to space 31 which communicates with the discharge pipe 36 and collector pipe 37. When the piston commences to retract the greater pressure in space 31 will seat the discharge valve 108 and the cycle will be repeated. If however there is no oil pressure in the space 93 and the rod 97 will move outward thus causing the lugs 103 to raise the arms 106 whereby to hold the suction valve 107 permanently from its valve seats, thus causing permanent communication between the suction annulus 30 and the interior of the cylinder sleeve 29. As long as this condition exists gas will enter the cylinder on the inward movement of the piston but will be forced back from the cylinder to the suction annulus on the outward stroke of the piston, thus nullifying the working effect of the piston.

In the operation of the device the amount of work required of the compressor will determine the pressure of the gas within the interior of the casing, which determines the extent to which bellows 70 will be collapsed or expanded. The degree of collapse of the bellows 70 determines the position of the valve land 80. The land 80 may be in such position as to uncover one or more of the slots 90 (there being six such slots for a six-cylinder compressor, only one of which is herein illustrated for clarity). Each slot so uncovered permits the application of oil pressure to its associated piston 94 thus moving the inclined portion 100 to the left in Fig. 4 and permitting the spring 105 to move the arms 106 from engagement with the suction valve 107, thus causing the piston 28 to compress gas. It will be observed that the oil pressure exists only when the compressor crank shaft 17 is in operation, preferably the inherent characteristics of the construction being such that sufficient oil pressure to move the pistons 94 will not exist until a certain minimum speed of revolution has been achieved thereby causing the compressor parts to run freely under any load when the automotive engine is being cranked. As soon as the ignition is effective and idling speed of the engine is achieved oil pressure will exist so that cylinders 50 may be caused to operate against the compression load. At idling speed of the engine the entire system should be so designed that all of the pistons should operate to supply the maximum required refrigeration. Since the number of revolutions per minute is low the compressor will not displace a great volume of refrigerant gas and the load upon the refrigerating system will usually be greatest since a new supply of commodities may be placed in a refrigerator truck or the interior of an air conditioned tonneau will be at its hottest point. Therefore, the pressure of the gas in the suction annulus and the interior of cover 12 will be high and the bellows 70 will be collapsed to the greatest extent possible. This causes movement of valve rod 4 to the far right in Fig. 1, uncovering all of the grooves 90 and causing all of the pistons to compress refrigerant gas. As the speed of the engine increases or as the load on the refrigeration system drops at the same speed the pressure of the gas returned to the compressor will be lessened, bellows 70 will expand, land 80 will cut off one or more of the grooves 90 and one or more of the compression pistons will cease operating so as to maintain a substantially constant refrigeration output.

The position of nut 75 may be regulated so as to determine the degree of compression of spring 77 thereby setting the pressures at which the valve will cause unloading or loading of various cylinders against various types or capacities of refrigerating systems. Likewise the position of nut 78 may be so adjusted as to prevent the expansion of bellows 79 beyond a certain point, providing means whereby at least one or possibly several of the pistons will always operate. This latter feature may be found desirable in certain refrigeration applications.

Preferably I provide a plurality of grooves 115 on a portion of the valve rod 4, which are adapted to be engaged by a spring urged ball 116 retained in a bore in the wall of casting 10. This device provides means whereby the movement of the valve rod 4 occurs in definite steps. For example, it may require a change of two pounds per square inch in the suction pressure to cause movement of the valve rod to load or unload each cylinder, thereby preventing fluttering of the unloading mechanism.

It will be observed that I have provided a compressor comprising a main casting supporting the compressing mechanism consisting of a crank shaft and its journals and the piston, cylinder and valve assemblies, and the individual unloading mechanism associated with each compressing cylinder as well as the master valve mechanism for controlling the individual cylinder unloading mechanism. To this main assembly is attached one end cover having the oil carrying passages and the oil pump. Assembly of the end cover 11 to the casing 10 completes the connections whereby oil pressure may be applied to the individual cylinder unloaders. The remainder of the mechanism may be assembled simply by inserting the valve rod 4 into the longitudinal bore in casing 10, and as the end cover 12 carrying the pressure responsive bellows is brought into position slipping the slots of the crank 1 into position over the pins carried by the valve rod 4.

While I have illustrated and described herein a preferred embodiment which the invention may take it should be obvious to those skilled in the art that various modifications in arrangement and detail thereof may be accomplished. I claim as my invention all such modifications as come within the scope of the following claims.

I claim:

1. A compressor having a plurality of radially extending cylinders each of a plurality of which is adapted to be individually controlled to compress gas or to be unloaded, comprising a first assembly including a main casting, a crank shaft supported thereby, means forming a plurality of radially extending compression cylinders, compression pistons operatively connected to said crank shaft, suction valve and discharge valve assemblies carried by said main casting, a plurality of individual cylinder unloading means carried by said main casting, each comprising an unloader piston and means operated thereby to hold one of said suction valves open whereby to cause its associated compression piston to reciprocate idly, all of said unloader pistons extending toward

one end of said main casting, a master valve carried by said main casting, a first end cover for said main casting, a lubricant pump carried by said end cover and including means for establishing a driving connection of said pump to said crank shaft when said casting and cover are assembled, means forming a plurality of unloader cylinders in said cover, each in position to receive one of said unloader pistons when said casting and cover are assembled, said cover having a plurality of passages therethrough whereby fluid pressure created by said pump may be transmitted to said master valve and selectively therefrom to said unloader cylinders, a second end cover for said main casting, a suction pressure responsive device carried by said second cover and adapted to collapse or expand as the suction pressure of the compressor varies, and means operatively connecting said device to said master valve upon assembly of said second end cover to said main casting whereby to control the selecting action of said master valve.

2. A compressor having a plurality of radially extending cylinders each of a plurality of which is adapted to be individually controlled to compress gas or to be unloaded, comprising a main casting, suction valves and discharge valves carried by said casting, one of each of said valves being associated with each of said cylinders, a plurality of individual cylinder unloading means each operable to hold one of said suction valves open under predetermined compressor operating conditions and each including a piston, a master valve, a first end cover for said main casting, a lubricant pump carried by said end cover, said cover having a plurality of unloader cylinders therein adapted to receive said pistons when said casting and cover are assembled, said cover having a plurality of fluid flow connections associated with said pump, said master valve and said unloader cylinders so that fluid may be pumped to said master valve and from there to individual unloader cylinders selected by said master valve, a second cover adapted to be secured to said main casting on the end thereof opposite said first cover, means responsive to compressor suction pressure carried by said second cover and means operatively connecting said last mentioned means to said master valve upon assembly of said second end cover to said main casting so that said last mentioned means is operable to control said master valve in response to compressor suction pressure.
